CHILD'S BLANKET OR SIMILAR ARTICLE

Elsa Foster, 306 W. 75th St., New York, N.Y.

Filed May 16, 1960, Ser. No. 60,599

Term of patent 14 years

(Cl. D92—2)

FIGURE 1 is a top plan view of a child's blanket or similar article, showing my new design; and

I claim:

The ornamental design for a child's blanket or similar article, as shown.
